PIN HOLDER FOR BOWLING PIN SETTERS

Rupert E. Rundell, Rockville Centre, N. Y., assignor to American Machine & Foundry Company, a corporation of New Jersey

Application October 16, 1940, Serial No. 361,371

14 Claims. (Cl. 294—65)

This invention relates to bowling pin setters of the type having a spotter device for gripping the pins and transferring them to the bowling alley, and a respotter device for picking up the standing pins after a ball is thrown to permit removal of the fallen pins, more particularly to the pin holders thereof.

In an earlier type of bowling pin setter the pin holders of the spotter device are mounted upon an invertible carrier into whose holders the pins are inserted in inverted position for inversion into upright position during inversion of the carrier and setting of the pins upon the alley during the descent of the carrier. The pin holders of the carrier are equipped with suction-actuated pistons employed to close the grippers with which the holders are provided, upon the heads of bowling pins and grip the same and transport the gripped pins to predetermined positions on the bed of a bowling alley. However it has been found that such pistons present difficulties in that their machining requires close tolerances, as they must closely fit the cylinders wherein suction is applied. Moreover, there is leakage of air between the piston and its cylinder which may impair the suction behind the piston to such an extent that the piston will not be displaced sufficiently to close the grippers on the pin, or the leakage may be so great past one piston that it will impair the suction on all the other pistons to such an extent that no pin will be gripped. Another virtue of the diaphragm is that it has less weight and needs less suction to be actuated. There is no friction to be overcome as in the case of a piston. Due to these limitations there has been used a piston of a diameter considerably less than the diameters of the diaphragms employed in the present constructions, wherefore a greater force is available for actuating the grippers with the diaphragm. Accordingly, it is an object of the invention to provide diaphragms which are actuated to control the operation of the grippers.

Still another object is to provide the pin holders of the respotter device, which may consist of cups or receptacles mounted on the carrier and arranged to engage the head ends of standing pins following the throwing of the ball and elevate the same to permit sweeping of the fallen pins into the pit of the alley, with diaphragms which control the operation of grippers for gripping the standing pins. In this connection a further object is to provide for suction actuation of the diaphragm of each cup, which may be free to move horizontally upon engaging an off-spot

pin to center itself with respect to the same, at any position to which the cups may be displaced by engagement with the heads of off-spot pins.

The grippers of the spotter and respotter may be actuated electromagnetically, and it is a further object to provide electro-magnetic devices for this purpose. In the case of the spotter, the grippers may be actuated by solenoids controlling the operation of the grippers which close upon the pins and transport them to predetermined positions on the bed of the alley. The cups of the respotter, which may be free to move upwardly upon engaging the head ends of the pins upon the alley during the descent of the carrier and are displaced horizontally by engagement with the heads of off-spot pins, are maintained in elevated position by an electro-magnet which is energized while the grippers are being actuated to grip the pins through the agency of a solenoid.

With these and other objects not specifically mentioned in view, the invention consists in certain constructions and combinations hereinafter fully described and then specifically set forth in the claims hereunto appended.

In the accompanying drawings which form a part of this specification and in which like characters of reference indicate the same or like parts:

Fig. 1 is a vertical section of one of the improved pin holders of a spotter in inverted position;

Fig. 2 is a vertical section of one of the pin holders or cups of the respotter having its funnel in engagement with an off-spot pin;

Fig. 3 is a vertical section of a modified form of spotter cup provided with electromagnetic means for actuating the grippers; and

Fig. 4 is a sectional view of a modified form of respotter cup having its funnel in engagement with an off-spot pin and equipped with a solenoid for actuating the grippers and an electromagnet for retaining the cup in the elevated position to which it is lifted by engagement with the head end of a standing pin.

Referring to Fig. 1 wherein there is shown one of a series of spotter cups or receptacles which may be fastened upon an invertible carrier, such as fully described in the patent to G. J. Schmidt, No. 2,217,709, issued October 15, 1940, each of the spotter cups is fastened to the carrier 1, so that they will be in inverted position when the table is inverted for admission of the head ends of bowling pins. Each of the cups has a neck 3 on which is fastened a base 5 carrying a tubular member 7 which has a flange fastened to the

base and is shaped to admit the head end of the inserted pin. A flexible diaphragm 9, which is formed of suitable impervious material such as rubber, Neoprene, or canvas has its rim secured between the base member and the tubular member and has metal disks 11 and 13 fastened to its central portion together with an abutment 15 having an upwardly inclined flange, by rivets 17. Grippers 19 pivotally mounted on lugs 21 of the member 7 have jaws arranged to enter perforations 23 in the tubular member and engage the head end of the pin, and their other ends are disposed between the flange of the abutment member 15 and the disk 13 for actuation by the diaphragm. A spring 25 seated against the neck 3 urges the diaphragm upwardly and thereby normally maintains the grippers in open position. A duct 27 in the neck 3 is connected to a suitable source of suction, not shown, and communicates through a hole 28 with the space behind the diaphragm, that is the space between the base member and the diaphragm, which may be termed a "suction chamber." At the proper time, suction is applied to this chamber for closing the grippers upon the inserted pin, to grip the same. Thus the flange of the abutment 15 presses down upon the opposed ends of the grippers which slide over the disk 13, which thus protects the diaphragm against rubbing and wear, and the gripper jaws are closed upon the pin. By providing metal disk 11 on the inner face of the diaphragm, injury of the latter by the rivets is prevented and the impervious character of the diaphragm is maintained.

Suitable mechanism for controlling the application of suction to the individual cups is shown in the co-pending application of P. M. Nejedly, Serial No. 339,344, filed June 7, 1940, to which reference may be had for a complete description of the details thereof. To the upper end of the base member 7 is fastened a tapered hood 29 which may be equipped with leaf springs 31 having studs 33 engaging the butt end of the inserted pin for maintaining it in properly centered relation relative to the cup during the inversion of the carrier, the construction of said springs constituting the subject matter of my co-pending application, Serial No. 326,135, filed March 21, 1940, and the suction is cut off in the space behind the diaphragm whereupon the grippers are opened and the pins are left upon the alley during the ascent of the table to initial position.

Referring to Fig. 2, wherein is shown one of a series of cups or receptacles of the spotter, each of the cups has a funnel 50 normally resting upon a lower support or plate 52 which is supported from the carrier and suitably perforated at 54 to admit the head end of the standing pins during the lowering of the carrier following the throwing of a ball. The funnel 50 is fastened to a base member 56 which has a suitable flange 58 and lugs 60 in which are pivotally mounted the grippers 62. The jaws of the grippers are arranged to enter the perforations 64 in the base member 56 and grip the head end of the pin. The other ends of the grippers are disposed within slots in the flange 58 and engage an abutment member 66 which is fastened, together with disks 68 and 70, to a flexible diaphragm 72 which may be formed of rubber, Neoprene, canvas or other suitable impervious material. The rim of the diaphragm is secured between the flange 58 and a cover 74 by suitable rivets 76. A leaf spring 78, which is connected at its mid section to the diaphragm by a rivet 81 passing through the disks 75

68, 70 and the diaphragm, has its ends disposed in engagement with the cover member 74 and is thereby suitably stressed to urge the grippers into open position for admission of the head end of a pin. At the margin of the flanged member 58 there is provided a circular sealing ring 80 which is arranged to engage the plate 82 when the cup is elevated by a standing pin. It may be noted that the members 52 and 82 are fastened to a carrier in the manner shown in the patent to G. J. Schmidt, No. 2,217,709, issued October 15, 1940, whereby each of the cups is supported by the carrier into position to engage and to be elevated by a standing pin to bring its sealing ring 80 into engagement with a member 82. It will be noted that the funnel normally rests on the member 52 and has a limited horizontal movement thereon whereby the pocket will be centered with respect to off-spot pins on the bed of a bowling alley by engagement of the funnel 50 with the standing pin during the descent of carrier. When the sealing ring engages the member 82 it provides in effect a suction chamber above the cover 74. A plunger 84, which has a sliding air tight fit in a casing 86, fastened to the member 82 normally projects into engagement with the cover 74 and is pressed upwardly during the descent of the carrier with the members 52 and 82 thereon, whenever the cup engages a standing pin. Normally, the member 84 is maintained in a position projecting from the casing 86, by balanced springs 88 and 90 engaging a collar 92 fastened on the member 84 whereby holes 94 in the tubular portion at the lower end of the latter are held in a position in which they are closed by the casing 86. When the member 84 is pressed upwardly, the holes communicate with a duct 96 in the casing 86 and the notches 98 in the lower end of member 84 permit the application of suction through the perforations 100 in the cover 74 to the diaphragm whereby atmospheric pressure on the exterior face of the diaphragm urges it upwardly and thereby closes the grippers 62 upon the head end of the pin. Since the construction of the plunger 84 and casing 86 and the mechanism for applying suction thereto is similar to that shown in the patent to G. J. Schmidt, No. 2,217,709, referred to above, further description is deemed unnecessary except to note that with the construction just described, suction will be applied to the diaphragm in any position to which the funnel or hood 50 may be displaced by engagement with an off-center or off-spot pin on the bowling alley.

Referring to Fig. 3, the spotter cup 150 is one of a series of ten or any other suitable number of cups fastened to the carrier 152 which is of a construction shown in the patent to G. J. Schmidt, No. 2,217,709, referred to above, and invertible to position the cups 150 in an inverted position at which the bowling pins are inserted. On lugs 154 of the cup 150 are pivoted grippers 156 whose jaws are movable through slots 158 into engagement with the head end of the inserted pin. A solenoid 160 has a core 162 which carries a plate 164 and a cup shaped member 166, the latter engaging the head of the inserted pin. The tails 168 of the grippers are disposed between the plate 164 and the upwardly bent flange of member 166 and the spring 170 in the base of the cup urges the core of the solenoid upwardly and thus normally maintains the grippers in an open position. To the upper end of the cup is fastened a hood 172 which is provided with leaf springs 174 carrying studs 176

engaging the butt end of the inserted pin maintaining it in centered position during the inversion of the carrier 152. The construction of the leaf springs 174 forms the subject matter of my co-pending application, Serial No. 326,135, filed March 21, 1940. A cam 178, which is suitably driven in timed relationship to the operation of the mechanism for inverting the table and turning it back to upright position, has a raised lobe 180 which engages a cam follower 181 on a contact maker 182 carrying contacts 186 and 188, which are insulated from each other and connected by wires 190 and 192 to the winding of the solenoid 160, and thereby raises the contacts 186 and 188 into engagement with the contacts 194 and 196 which are insulated from each other and connected to the power lines 198 and 200, respectively. Thus the solenoid is energized to draw the core downwardly and thereby close the grippers upon the inserted pin. The extent of the cam lobe 180 is sufficient to maintain the grippers in closed position while the table 152 is being inverted and while it descends into position to deposit the gripped pins upon the bed of the bowling alley. As the cam follower 181 on the contact maker 182 rides off the cam lobe 180, the contacts 186 and 188 are disengaged from the contacts 194 and 196 and the circuit through the solenoid is broken, whereupon the spring 170 again urges the grippers into open position at which they remain until the next bowling pin is inserted in the inverted cup.

Referring to Fig. 4, the hood 250, which is one of a series of ten or any other desired number corresponding to the number of bowling pins upon the bed of the alley, is fastened to a cup 252, and the hood normally rests on a bottom plate 254 having a perforation 256 which admits the head end of a standing bowling pin on the alley. The cup 252 is provided with grippers 258 which are movable through slots 260 into engagement with the head end of a pin within the cup. The grippers are pivoted upon lugs 260 and are provided with tails 264 which project into engagement with a cup shaped member 266 which has a downwardly bent flange underlying the tails 264. Member 266 and plate 268, the latter overlying the tails 264 of the grippers are fastened to the core 270 of a solenoid 272 arranged within the base of the cup. A spring 274 engaging the plate 268 urges the solenoid core downwardly and thereby rocks the grippers into open position through the engagement of the plate 268 and the member 266 with the tails 264 of the grippers. The funnel 250 normally rests on the member 254 and has a limited horizontal movement thereon to permit displacement of the funnel and its cup into centered relationship to the bowling pin in which it engages upon the bed of the alley. The funnel or hood 215 and its cup are also free to move vertically off the plate 254 upon engaging the head end of a standing bowling pin on the alley during the descent of the carrier upon which the plate 254 is supported in a manner similar to that shown in the patent to G. J. Schmidt, No. 2,217,709. As the carrier descends the pin engages the member 266 and thus raises the cup until the steel plate 276 at its upper end is brought into contact with the core 278 of the electromagnet 279 which are supported on the plate 280 fastened to the carrier, together with the plate 254 in the manner shown in Patent No. 2,217,709, referred to above. At this time the raised lobe 281 on a cam 282 which is suit-

ably driven in timed relationship to the operation of the carrier, engages the cam follower 284 on the contact maker 286 and raises the contacts 288 and 290, which are carried thereon and insulated from each other, into engagement with a contact 292. A supply line or main 294 connected to a suitable source of current, is connected to contact 292 and has a lead 296 connected in parallel to the winding of the electromagnet 298 which is connected by lead 300 to the contact 288. The contact 290 is connected to one end of the winding of the solenoid 272 by a lead 302 and the other end of the solenoid winding is connected to the line 304 which is connected like main 294 to the source of current. Thus the grippers are closed upon the head end of the pin and the plate 276 of the cup is retained electromagnetically on the core 278 of the electromagnet while the pins are raised off the alley to permit the sweeping of the fallen pins. The cam lobe 281 maintains the contacts 288 and 290 in engagement with the contact 292 until the table again descends and deposits the pins once more upon the bed of the alley, at which time the cam follower 284 rides off the cam lobe and the grippers are opened and the plate 276 is released from the electromagnet core 278. The funnel 250 then re-engages the plate 254 when the carrier then again ascends.

In addition to the materials mentioned above as suitable for the diaphragm, leather or corrugated metal may be used. It may be noted that besides preventing rubbing of the diaphragm by the grippers, the plate 13 shown in Fig. 1 and the plate 70 shown in Fig. 2 assure uniform movement of the grippers into engagement with the pin. If the grippers directly engaged the diaphragm unequal movement thereof might result if any of the portions engaging the grippers should collapse while closing the grippers. The plate 11 shown in Fig. 1 may be made much smaller than the plate 13, if desired, without affecting the operation of the grippers, and the same is true of the plate 68 in Fig. 2 with respect to the plate 70.

45 What is claimed is:

1. In a bowling pin setter, the combination with an invertible receptacle adapted while in inverted position to admit the handle end of a bowling pin, of a set of leaf springs mounted on said receptacle to engage the butt end of an inserted pin and maintain the same in centered position therein, a set of grippers adapted to grip the inserted handle end of a pin, and means for actuating said grippers to grip said pin.

50 2. In a bowling pin setter, the combination with a receptacle adapted to admit a portion of a bowling pin, of a set of grippers mounted on said receptacle and adapted to grip the inserted pin, and electromagnetic means for actuating said grippers to grip the inserted pin.

65 3. In a bowling pin setter, the combination with a receptacle adapted to admit a portion of a bowling pin, of a set of grippers mounted on said receptacle and adapted to grip the inserted bowling pin, a flexible diaphragm arranged to control the operation of said grippers, and means for moving said diaphragm to control the operation of said grippers.

70 4. In a bowling pin setter, the combination with a receptacle adapted to admit a portion of a pin, of a set of grippers mounted on said receptacle and adapted to grip the inserted bowling pin, a diaphragm arranged to control the operation of said grippers, and means for moving

said diaphragm to close said grippers and grip the inserted pin.

5. In a bowling pin setter, the combination with a series of receptacles each adapted to admit a portion of a bowling pin, sets of grippers mounted on each of said receptacles and adapted to grip an inserted bowling pin, flexible diaphragms on each of said receptacles, each of said diaphragms being arranged to control the operation of said grippers, and fluid means for moving said diaphragms in unison to control the operation of grippers.

6. In a bowling pin setter, the combination with a series of receptacles each adapted to admit a portion of a bowling pin, sets of grippers mounted on each of said receptacles and adapted to grip an inserted bowling pin, flexible diaphragms on each of said receptacles arranged to control the operation of said grippers, and fluid means for moving said diaphragms in unison to close said grippers and grip the inserted bowling pins.

7. In a bowling pin setter, the combination with a cup adapted to admit the handle end of a bowling pin, of a set of grippers mounted on said cup and adapted to grip the inserted end of a bowling pin, a flexible diaphragm engaging said grippers, a spring urging said diaphragm into position to open said grippers, and suction means for moving said diaphragm into position to close said grippers upon the end of an inserted pin and thereby grip the same.

8. In a bowling pin setter, the combination with a cup adapted to admit the handle end of a pin, of a set of grippers mounted on said cup and adapted to grip the inserted end of a pin, a spring-pressed member engaging said grippers and urging them into open position, and a solenoid having its core connected to said member and adapted when energized to move said member sufficiently to close the grippers upon the inserted pin and thereby grip the same.

9. In a bowling pin setter, the combination with a series of receptacles each adapted to admit a portion of a bowling pin, of sets of grippers mounted on each of said receptacles and adapted to grip an inserted pin, and an electromagnetic means for actuating said grippers in unison to grip bowling pins inserted in said receptacles.

10. In a bowling pin setter, the combination with a receptacle adapted to admit a portion of a bowling pin, of a set of grippers mounted on said receptacle and adapted to grip the inserted pin, a member coacting with said grippers to operate the same on displacement of the central portion of said member, said member having a flexible margin fastened in said receptacle, and mechanism for displacing the central portion of said member to cause the same to close said grippers.

11. In a bowling pin setter, the combination with a set of grippers adapted to grip a bowling pin, of a flexible member adapted to operate said grippers, and means for applying fluid pressure to said member for actuating said grippers.

12. In a bowling pin setter, the combination with a set of grippers adapted to grip a bowling pin, of a flexible member connected to said grippers, and means for displacing said flexible member to operate said grippers.

13. In a bowling pin setter, the combination with a device for gripping a bowling pin, said device including a flexible member, of means for applying fluid pressure to said member to grip the bowling pin.

14. In a bowling pin setter, the combination with a set of grippers adapted to grip a bowling pin, of a flexible diaphragm, a rigid member carried by said diaphragm and arranged to engage said grippers, and means for applying fluid pressure to said diaphragm to displace said member and cause it to close said grippers.

RUPERT E. RUNDELL.
